(57) **CLAIM**

The ornamental design for a weed puller, as shown and described.

DESCRIPTION

FIG. 1 is a front, left and top perspective view of a weed puller, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an exploded view thereof.

The claim is directed to shaded surfaces. Any unshaded surfaces shown in broken or between solid and broken lines forms no part of the claimed design.

1 Claim, 8 Drawing Sheets(56)
